UNITED STATES PATENT OFFICE

WILLIAM F. PUNTE, OF SYRACUSE, NEW YORK, ASSIGNOR TO CONTINENTAL CAN COMPANY, INC., OF NEW YORK, N. Y., A CORPORATION OF NEW YORK

METAL CONTAINER

Application filed April 2, 1931. Serial No. 527,304.

The invention relates to new and useful improvements in a metal container, and more particularly to a metal container wherein the cover or end is secured thereto by a sealing strip or band which is forcibly removed from the container for releasing the cover therefrom.

An object of the invention is to provide a container of the above type wherein a sealing gasket is forcibly pressed into sealing engagement with the body of the container and cover, and is so disposed that upon removing the sealing strip the gasket is uncovered so that it can be readily removed, thus breaking any vacuum in the container and facilitating the removal of the cover therefrom.

A further object of the invention is to provide a container of the above type wherein the upper face of the projecting portion of the cover overlying the flange on the container body, and also the upper portion of the retaining strip, are substantially flat, and wherein said strip is held on the container by a bead formed in the cover which is located beyond the flange and which projects below the under face of the flange.

In the drawing:—

Figure 1 is a side view of a container partly in section and embodying the improvements.

Figure 2 is an enlarged sectional view of a portion of the container showing the cover, the retaining strip and the sealing gasket in place prior to the sealing of the container.

Figure 3 is a similar view but showing the lower portion of the retaining strip as pressed into sealing position for sealing the container and locking the strip to the container.

Figure 4 is a view similar to Figure 2 but showing the retaining strip and sealing gasket removed.

The invention is directed to a metal container wherein the body portion is provided with a flange at the upper open end thereof. Seated in the open end for closing the same is a cover which has a central depressed portion fitting the opening in the container.

The cover is also provided with a portion which projects beyond and overlies the flange on the body of the container. The outer por-

tion of the cover is curled downwardly, thence inwardly and upwardly to form a bead which lies beyond the edge of the flange of the container body. This bead is of greater thickness than the flange on the body, and therefore the lower edge of the bead is beneath the lower face of the flange. A sealing gasket is placed in the recess between the bead and the wall of the body and beneath the flange. A sealing strip which is, when attached to the container, substantially U-shaped in cross section, overlies the cover and extends beneath the bead and the flange and is pressed against the sealing material for forcing the sealing material into tight sealing engagement with the flange and the bead. The bead also serves the function of holding the retaining strip on the container until it is forcibly removed therefrom.

Referring more in detail to the drawing, a container is shown which includes a body portion 1 having an end 2 secured thereto by a double seam 3. The body wall 1 at the upper edge thereof is rolled or bent outwardly to form a flange 4 which overhangs the outer wall of the container body, that is the flange projects outwardly and is substantially horizontal at the extreme outer portion thereof. The container is closed by a cover or end 5 which is formed with a depressed portion 6 fitting within the open end of the container. The cover has a portion 7 which overlies the flange and projects beyond the end of the same. The extreme outer portion of the cover is curled downwardly, inwardly and upwardly to form a bead 8. This bead is disposed beyond the edge of the flange 4. The top face of the cover portion overlying the flange is substantially flat, and the bead is of such thickness that the extreme lower portion thereof is well below the lower face of the flange 4 of the container body. This forms a recess in which a gasket 9 is placed. The gasket 9 is for the purpose of sealing the opening between the end of the flange and the bead, and thus sealing the cover to the container body.

The cover is secured to the container body by a retaining strip 10. The retaining strip is substantially U-shaped in cross section 100

when attached to the container. It includes an upper portion 11 which is substantially flat, and which snugly fits the upper face of the cover portion 7. It is curved to form to 5 a shaping of the bead at its extreme outer portion, and is provided with a substantially horizontally extending portion 12 which underlies the flange 4 and the bead 8. After the strip has been placed on the container the portion thereof is deflected or pressed upwardly, thus forcing the gasket into tight sealing contact with the flange and the bead. This upwardly deflected portion serves the function also of holding the retaining strip 10 on the container until it is forcibly removed therefrom. It will be noted that in Figure 2 of the drawing that the distance between the portions 11 and 12 of the retaining strip, when applied to the container, is slightly less than the distance from the upper face of the cover portion 7 to the extreme lower edge of the bead 8. Therefore the bead 8 serves as a retaining means to hold the strip in place on the container. In Figure 2 of the drawing 15 25 the parts are shown with the container strip in place but before it has been reformed to seal the container. In Figure 3 it is shown as tightly gripping the gasket and locked in place by the deflecting or deforming of the 30 lower part of the retaining strip. In Figure 4 the retaining strip and gasket is shown as removed, which can be done by grasping the end 10a of the retaining strip and forcibly pulling the same from the container. This 35 can be done by hand so that the retaining strip can be readily removed. When the retaining strip is removed the gasket can be readily removed as it is uncovered by the removal of the retaining strip. When the 40 gasket is removed any vacuum which is present in the container will be broken and the cover can be readily lifted from the container. It can be readily replaced also for the purpose of reclosure purposes. 45 Having thus described the invention, what I claim as new and desire to secure by Letters Patent, is:—

A metal container comprising a body portion having a projecting flange at its upper end, a cover having a depressed central portion fitting within the container body and a portion projecting beyond the flange of the container body, the outer edge of which is curled downwardly and inwardly to form 50 55 a bead disposed beyond the edge of the flange on the body and of greater thickness than the flange, a sealing gasket beneath the flange on the can body for sealing the space between the edge of the flange and the bead on the 60 65 cover and a retaining strip overlying the cover and extending beneath the flange on the can body, a portion of the retaining strip beneath the flange and inside of the bead being deflected upwardly for pressing the sealing material into sealing contact with the

flange and bead and for holding said strip in place on the container until forcibly removed therefrom.

In testimony whereof, I affix my signature.

WILLIAM F. PUNTE.
